UNITED STATES PATENT OFFICE

ROY E. DRANNON AND NAT W. KENISON, OF BEXLEY, OHIO

HAIR WAVING AND CURLING MACHINE

Application filed March 17, 1932. Serial No. 599,424.

This invention relates to a hair waving machine and has for its object to provide an apparatus of this type which will be capable of imparting a wave to hair in a rapid, efficient and safe manner.

Another object is to provide a machine which will be adaptable for imparting a plurality of individual waves at one time and which will employ substantially or identically the same amount of heat for each wave.

Another object is to provide a machine of the type described which will employ steam as a heating medium and which will render the steam available to the hair undergoing treatment in such manner as to eliminate the probability of burning, singeing or otherwise injuring either the hair or the scalp from which the hair arises.

More specifically, it is the object of this invention to provide a hair curling machine which will direct a supply of steam for heating locks of hair entrapped in a plurality of individual curling irons, to arrange the irons in series in order that a steam circuit may be established therethrough, and to provide means for controlling both the rate of steam generation and the rate of supply to the irons.

A further object is to provide curling irons which will accept a wide lock of hair,—that is, a lock which, if viewed sectionally at the scalp, will have a pronounced elongated shape, said irons being adaptable to impart any desirable tightness to the lock during placement therein, and which will permit a definite rolling and tightening thereof over the entire length of the lock.

A further object of the invention is to provide means for generating steam in accord with the requirements of the curling irons, to provide the requisite number of regulators therefor, and to provide a further means for instantaneously relieving the irons of a steam supply in case of emergency.

Other objects and advantages either directly related or indirectly implied will become hereinafter more fully apparent as reference is had to the accompanying drawings wherein our invention is illustrated, and in which

Figure 1 is a vertical section through my

improved hair curling machine having my improved curling irons diagrammatically illustrated as being connected thereto, said section taken along the line 1—1 of Fig. 2,

Fig. 2 is a vertical section taken along the line 2—2 of Fig. 1,

Fig. 3 is a detail showing the arrangement of the pump valves indicated in Figs. 1 and 2,

Fig. 4 is an elevation of my improved curling iron,

Fig. 5 is an elevation of the casing for the iron of Fig. 4.

Fig. 6 is an elevation of the clamp upon which the casing of Fig. 4 resides when assembled.

Fig. 7 is an elevation of the scalp protector upon which the clamp shown in Fig. 6 resides when assembled,

Fig. 8 is a section taken through the clamp and protector shown in Figs. 6 and 7 respectively, when assembled with a lock of hair extending therethrough,

Fig. 9 is a transverse section through the iron and casing shown in Figures 3 and 4 respectively.

Fig. 10 is an elevation of the hair tightening tool.

Fig. 11 is a plan view of two irons and casings assembled and connected to each other.

Fig. 12 is a modification of the machine illustrated in Figs. 1 and 2, taken from the rear of the cabinet which is partially broken away for illustration purposes.

Fig. 13 is a vertical section taken along the line 13—13 of Fig. 12, and

Fig. 14 is a partial frontal view of the cabinet shown in Figs. 12 and 13.

In the views the character 1 refers generally to a cabinet in or near the bottom of which is supported a flash boiler 2 heated by a burner 3. Extending into the boiler 2 is a water supply line 4 which leads from a reservoir 5 by way of reversely seated check valves 6 between which is placed a pump 7.

The handle 8 for this pump extends outwardly from the cabinet so that an operator may control the feeding of water and hence determine the rate of steam generation by the boiler 2. A steam line leads outwardly from

the boiler 2 to a union 9 where it divides into a plurality of lines 10 which extend outwardly from the cabinet at the points 11. It will be noted that these lines 10 are carried outwardly of the cabinet near the top thereof in order to receive the benefit of the waste heat from the generator to prevent condensation therein.

From the points 11 the lines are connected 10 to a plurality of curling irons assemblies to be hereinafter more fully described and to return lines 12 which lead from these irons into the cabinet at points close to the supply tank 5. The length of these lines outwardly 15 of the cabinet 1 together with their exposure to the water in the tank 5 provides a cooling action which promotes condensation and hence induces a flow of steam through the curling irons. An even and continuous flow 20 through each of the irons in series is assured because stoppage at any point stops the flow through all irons in series therewith so that the pressure in the line immediately rises unduly and the degree of rise is shown on an indicator 13 located in a wall of the cabinet 25 said indicator being visible to the operator stationed at the pump handle. The supply of steam from the boiler may be instantaneously arrested or reduced in volume by the 30 actuation of a handle 14, outwardly of the cabinet, which controls a valve 15 in the line 10. A safety relief valve 16 is provided on the boiler for this or any other emergency.

In Figs. 12, 13 and 14 the parts corresponding to similar parts in Figs. 1 and 2 are primed. The salient feature of the form of these figures is the illustration of the convenient employment of the boiler pressure to effect complete circulation. Thus the feed line 4' may connect directly into a municipal water system, and the final tank 33 may become simply a drainage means from which the water collecting therein is evaporated by the waste heat from the burner 3' or otherwise disposed of. Since pressure from the boiler is solely relied upon in this instance for circulation of steam through the several curling irons, the return line 12' may enter the cabinet 1' at points close to the points 11' 50 as shown in Fig. 14.

The curling iron assembly is composed of a curling iron and its casing as shown in Figs. 3 and 4 in which the iron is composed of a hollow tubular member 17 having a large 55 cross-section at each end and gradually diminishing in size towards its mid-section, and a clamp 18 which ensnares the end of a lock of hair against the tubular member 17 in order that the hair may be rolled about the iron. 60 This shape together with the pivoted clamp permits the wrapping of a wide lock of hair spirally therearound as distinguished from the helical wrapping sometimes seen and which has been found to be inferior to the 65 spiral method.

At each end of the tubular member 17 bearings 19 are provided for reception by resilient journals 20^a provided at each end of a casing 20. The casing 20 is preferably insulated with a resilient packing 21 which extends outwardly of the walls so that when the casing is assembled about the iron a packing is formed along the edges 21. Thus when the end clamps 22 are swung into locking engagement the casing constitutes a steam tight 75 compartment.

The tubular member 17 is provided with perforations 23 which vent steam into the casing 20 from the line 10, the line 10 being connected into the tubular member 17 by means of a frictional or other desirable type of connection. The outlet end of the tubular member 17 is connected to a flexible connection 24 which is a part of the line 10 and which leads into another assembly, finally emptying into 85 the return line 12.

A pad 25 having a slot 26 therein and upstanding side-walls 27 constitutes a scalp protector. A lock of hair is drawn through the slot 26 whereupon a clamp 28 is locked therearound. This clamp is of metal having a resilient covering over each of its jaws, the covering extending outwardly to form wings 29 for reception by the ledge 27 around the pad 25, the portion 30 adjacent the metal jaws being formed as a cradle to receive the casing 20. A wrench 31 is provided to rotate the iron on its bearings by means of a pin 32^a of a bayonet joint 32 in order that the casing may be drawn tightly against the cradle 30. 90 Where the curling irons are in series in each of two steam lines the application of the irons to the hair of the head at each side of the latter is facilitated and many parts and connections dispensed with, such as are present 95 when the irons are in parallel. It is an aim of our invention to secure such advantage by adequate control of the heating means so as to secure the proper heating of the individual iron notwithstanding they are in series.

While we have described the illustrations with great particularity it will be understood that we desire to be protected as defined by the scope of the appended claims.

What we claim is:

1. In a hair curling machine, a plurality of curling irons separably and flexibly connected in series and means for directing and controlling a heated fluid through said irons to secure substantial uniformity in the heat of said iron.

2. In a hair curling machine, a plurality of curling irons connected in a flexible steam line, said irons being substantially equally spaced in the line in series, means for rendering a supply of steam available to said irons, and means including a condenser for inducing a flow through said irons.

3. In a hair curling machine, a flash boiler, a source of water supply for said boiler, a

5 pump for delivering water from said source of supply to said boiler, and a steam line from said boiler to said source of supply, said steam line including a plurality of curling irons connected in series.

10 4. In a hair curling machine, a steam generator, a plurality of curling irons in series connected to said generator, valvular means for controlling the flow of steam through said irons, and a pressure relief valve on said steam generator whereby a substantially uniform temperature is maintained in all of said irons.

15 5. In a hair curling machine, a flash boiler having a plurality of curling irons connected in series therewith, a source of water supply for said boiler, means for supplying water to said boiler in accord with the requirements of said irons, a gauge for indicating the pressure in said boiler, means for instantaneously arresting the flow of steam from said boiler to said irons, and a pressure relief valve on said boiler.

20 6. In combination, a cabinet having a flash boiler therein, a water supply tank for said boiler, steam lines leading upwardly from said generator and outwardly of said cabinet, a plurality of curling irons connected in series in said lines, and return lines from said irons to said supply tank, said return lines entering said cabinet at a point close to said tank whereby condensation therein by the cooler air outwardly of said cabinet is promoted.

25 7. In combination, a cabinet having a flash boiler therein, steam lines leading from said boiler outwardly of said cabinet, a plurality of curling irons connected in series with said lines, a source of water supply for said boiler, means controllable exteriorly of said cabinet for directing water from said source of supply to said boiler, an indicator visible to an operator of said pump for relating the steam pressure in said lines and means operable exteriorly of said cabinet for instantaneously arresting the flow of steam from said boiler to said lines.

30 8. In a curling iron, a hollow tube having enlarged ends and a gradually reduced mid-section, said tube being perforated along its length, and a clamp pivotally mounted on said tube, said clamp upon entrapping hair against said tube spreading said hair to require a helical winding thereof.

35 9. In hair curling means, a curling iron including a perforated tube having a clamp pivotally mounted thereon for ensnaring hair against said tube, bearings at each end of said tube, a casing enveloping said iron in spaced relation therewith, resilient journals carried by said casing for said bearings and clamp means for compressing said journals about said bearings.

40 10. In combination, a curling iron including a perforated tube having a clamp pivotal-

ly mounted thereon for ensnaring hair against said tube, bearings at each end of said tube, a casing enveloping said iron in spaced relation therewith having journals for receiving said bearings, clamp means for maintaining said casing in assembled relation about said iron and means for rotating said iron when assembled in said iron.

45 11. In a curling iron assembly, a curling iron including a hollow tube having a clamp pivotally mounted thereon for ensnaring hair thereagainst, said tube having bearings at each end thereof and perforations along its length, a split casing enveloping said iron in spaced relation therewith, said casing carrying resilient packing along its edges to form a steam tight compartment when assembled, resilient journals in said casing for said bearings, clamps for maintaining said casing in compressed assembly with respect to itself and said bearings, means for rotating said iron in said casing, and a steam supply line connected to said tube at one end thereof.

50 12. In combination, a plurality of curling irons including hollow tubes perforated along their length and each having a clamp for ensnaring hair thereagainst, bearings at each end of said tubes, a split casing enveloping each of said irons, said casings each having resilient packing means along their edges and resilient journals for said bearings, means for clamping each of said casings in compressed assembly to form steam tight compartments, and flexible steam lines connecting each of said irons with the iron adjacent thereto.

55 13. In combination, a curling iron for receiving a lock of hair, a casing through which said hair extends enveloping said iron, a clamp outwardly of said casing for tightly gripping said hair, and means for rotating said iron to draw said casing tightly against said clamp.

60 14. In combination, a curling iron including a tubular member and a clamp pivotally mounted near one end thereof for ensnaring and spreading the end of a lock of hair along a substantial length of said tube, a steam tight casing for said clamp and said hair, a second clamp having resilient jaws forming a cradle and residing outwardly of said casing for tightly gripping said lock of hair, and means for rotating said iron to draw said casing into the cradle of said second clamp.

65 15. In combination, a curling iron including a tubular member and a clamp pivotally mounted near one end thereof for ensnaring the ends of a wide lock of hair along a substantial length of said tube over a region radiating from the mid-section thereof, a steam tight casing through which said hair extends, a metallic clamp having a heavy resilient covering around the jaws thereof residing outwardly of said casing for tightly gripping said lock of hair, and means for

rotating said iron to draw said casing against said clamp, the covering around said clamp being formed as a cradle to constitute additional steam packing for said casing.

- 5 16. In combination, a curling iron including a tubular member and a clamp pivotally mounted near one end thereof for ensnaring and spreading the ends of a lock of hair along a substantial length of said tube over
- 10 a region radiating from the mid-section thereof, a steam tight casing through which said hair extends, a clamp having resilient jaws residing outwardly of said casing for tightly gripping said lock of hair, means for
- 15 rotating said iron to draw said casing against said clamp, and a protective pad for placement between said clamp and the scalp from which said lock arises.
17. In combination, a curling iron including a tubular member and a clamp pivotally mounted near one end thereof for ensnaring the ends of a lock of hair along the length of said tube over a region radiating from the mid-section thereof, a steam tight casing
- 20 through which said hair extends, a clamp outwardly of said casing for gripping said lock of hair, a rubber covering for each of the jaws of said clamp extending outwardly to form wings, said iron being rotatable to
- 25 draw said casing against said clamp, and a pad between said clamp and the scalp from which said lock arises, the covering for the jaws proper being formed as a cradle to receive said casing and retain said wings
- 30 whereby a unitary structure is provided.
